UNITED STATES PATENT OFFICE.

WILLIAM H. ECKERT, OF NEW YORK, N. Y.

TELEPHONIC TRANSMISSION.

SPECIFICATION forming part of Letters Patent No. 292,212, dated January 22, 1884.

Application filed December 4, 1882. (No model.)

To all whom it may concern:

Be it known that I, WILLIAM H. ECKERT, of the city, county, and State of New York, and a citizen of the United States of America, have made a new and useful improvement in the art of long-line telephonic transmission, which consists in the method of and means for overcoming the effects of static induction arising upon the main line.

10 When an electrical impulse is thrown upon a line running in close proximity to the earth, owing to an electrical reaction between the line and the earth, the transmission of the impulse from one point of the circuit to another is retarded, and a considerable electricity is stored in and about the line, which will escape if the line is connected to earth upon removing the primary electrical source. If the primary source of electricity be removed 15 from the line, and the remote ends of said line are connected to earth, an inductive discharge will occur upon the line from its center toward both ends. The inductive discharge at the receiving-station is a secondary 20 current of the same direction as and closely following the primary current.

At the transmitting end of the line the current of inductive discharge is a quick current running from the center of the line in a direction 25 opposite to that of the primary current. These currents occurring at the two grounded extremities of a line I term, respectively, the "counter" and "tailing" currents of inductive discharge, and for convenience of description 30 I term them the "effects of static induction."

In the process of telephonic transmission electrical impulses of variable strength succeed one another with great rapidity. In case 35 telephonic transmission is effected by impulses all of one polarity, each succeeding impulse in the first half of the circuit is met and weakened by the counter current of inductive discharge due to the preceding impulse, while each succeeding impulse will so closely follow the tailing current of the preceding impulse that they will either be blended or the space separating the two primary impulses will be nearly filled by the tailing current. If telephonic communication is effected 40 by impulses alternately positive and negative,

as is generally the case, the tailings of a preceding impulse, at the receiving end of the line, will meet and partially neutralize the succeeding impulse, the polarity of the succeeding primary impulse being opposite that of the preceding. The tailing current, as well as the counter-current, in point of quantity and duration, depends upon the length of the line. Thus, if the length of the line be so 50 great as to afford a tailing current which will cause the blending of one impulse and a succeeding one, transmitted speech will lose its characteristic of articulate sound, and the counter-current will be so great as to materially 55 weaken the primary impulses upon which loudness of reproduced sound depends. Therefore, if the counter and tailing currents must wholly escape at the two extremities of the line, the limit of line-length upon which 60 telephonic transmission can be practically effected is soon reached.

To the end of enabling telephonic transmission upon lines of great length, I provide means for inductive discharge from many intermediate points along its length to earth, which consists in establishing permanent leak-branches of high resistance. By this means the inductive discharge of the section between two adjacent leak-branches occurs independently of the inductive discharge of the other sections, and, however long a line may be, the time and magnitude of the inductive discharge will depend only upon the length of its sections. Obviously, the shorter the main-line sections between leak-branches are the 75 less will be the interference from inductive currents.

I have ascertained that when employing leak-branches, which are formed as hereinafter specified, the best results are attained by employing leak-branches distributed over the line at a distance of about one-third of a mile apart, in which case they may be of a sufficiently high resistance as not to cause a too 80 great leakage of the primary impulses, while they permit the ready escape from line of the currents of inductive discharge. Leaks of 85 less resistance more widely separated, as by two or three miles, may be used; but the inductive discharge from each section would be slow and the quantity large, even if the leak- 90 95 100

resistance were so small as to divert the greater portion of primary impulses from the main line.

I have discovered that a series of leak-branches distributed along a line whose joint resistance is far greater than the resistance of a single leak-branch will free the line more readily of inductive-discharge currents than the single leak, and at the same time they will not cause as great weakening of the main-line current. Ten leak-branches, whose joint resistance is three hundred thousand ohms, I find will more efficiently free the line from inductive currents than a single leak of one hundred thousand ohms, and the leakage from line in the former case is only one-third as much as in the latter.

The means which I prefer for providing leaks when they are placed about one-third of a mile apart consist of an iron or other metallic pin set in or attached directly to a wooden telegraph-pole or a cross-arm thereof, and without the intervention of insulating material; or the pole and cross-arm may be of other material of high resistance; or, instead of supporting the line-wire directly upon a cross-arm, the wire may be supported by an intervening glass or other insulating support and joined to earth by any ordinary conductor containing a high resistance.

I will now describe my invention by reference to the accompanying drawings.

Figure 1 shows a battery telephonic transmitter, a magneto-receiver, and a main line provided with a series of leak-branches. Fig. 2 shows a main line and means of establishing the leak-branches. Figs. 3 and 4 show details of the iron-pin supports and lightning-arresters.

In Fig. 1, T is an ordinary contact or battery transmitter. B is a battery in a local circuit, embracing the primary of the induction-coil I. S is the secondary of the induction-coil I in the main line L. R is a magneto-telephonic receiver, and a b c d e are a series of leak-branches connecting the line to earth at intermediate points of its length.

Fig. 2 represents a line, L, supported by a glass insulator, G, mounted upon a pin, E, which is placed upon an ordinary cross-arm, A, and the arm A is supported upon a telegraph-pole, H. In the same figure H' is an ordinary wooden telegraph-pole. A' is a wooden cross-arm, and F' is an iron pin supported in the cross-arm, without the intervention of insulating material, to which the line-wire is directly connected. An earth-branch from the line L is therefore established directly through iron pin F', cross-arm A', and pole H'.

Instead of establishing a leak-branch through the cross-arm and pole, the line-wire L may be supported upon a glass hood, and an earth-connection may be effected through a branch line, as O, having a rheostat, Rh, of high resistance.

Figs. 3 and 4 represent the iron pin F' in

detail. Said pin is hollow, and in its lower end is fitted a stopper or plug of insulating material, to which is attached a metallic piece, V, connected directly to earth by wire W. V 70 is insulated from the iron pin F', and serves as a lightning-arrester.

A lightning-arrester must be employed upon every pole where the line is in direct contact with the pole, as it would otherwise be shattered by lightning.

Instead of employing an iron pin, F', as shown in Figs. 2 and 3, I may mount a cross-piece, J, having two wire-supports, Q Q', of tube-iron, upon a tube-iron shank, F', in the 80 lower end of which is fitted the insulating-plug K, carrying the lightning-arrester V, to which is connected wire W; and the iron shank F' may be set directly in the wooden telegraph-pole or upon a wooden cross-arm. 85

In Fig. 1 the arrows indicate the directions taken by inductive currents of discharge after the termination of a signaling impulse. Each section of the line is cleared by a discharge from its middle toward both ends and over the 90 leak-branches at its extremities.

The time of static discharge of a conductor is found to be about proportional to the square of its length. Thus if one conductor is twice the length of another, its time of static discharge 95 will be four times greater. Of course the magnitude of static discharge is proportional to the length of line. Therefore, by providing a line with many leak-branches, the time of discharge is greatly quickened, and the magnitude of the discharge at any point will be so slight as not to interfere with primary impulses, however rapidly they may succeed one another. For example, the section between branches a and b will discharge about four 105 times quicker than would the part of the line between branches a and e, if branch b were omitted; and if branch b be employed, the magnitude of the discharge of the line will be only about one-half as great at branch a as 110 when b is omitted.

As each pole upon which the line rests furnishes a leak-branch, the leakage of the line will vary as the number of leakage-poles employed, and I have found that the leak-branches may be so far increased as to prevent communication to a distant station. However, the more leak-branches there are the better will the line be cleared of inductive effects; and it is therefore necessary to ascertain the 115 greatest number of leak-branches that may be employed without rendering the system materially imperfect from the effects of leakage. This is a matter which can only be determined empirically for each particular line, though, as 120 above stated, generally, where ordinary poles are employed, the line may be connected with poles about one-third of a mile apart, or about every tenth pole.

If, instead of telegraph-poles, leaks of higher 130 resistance be employed, they may be placed much nearer together, and, in fact, if leakage

could be uniformly established throughout the entire length of line of an exceedingly high resistance, better results would be obtained.

I am aware that leak-branches have been 5 employed upon telegraph-lines for the purpose of enabling an increased rate of transmission. I therefore desire to disclaim the broad matter of a line for transmitting electrical signals in combination with a series of earth- 10 branches, and limit myself to a telephonic conductor provided with leak-branches.

While leak-branches have been known as an imperfect means for accelerating the transmission of ordinary telegraphic signals, it was only 15 ascertained by experiment that such leaks could be advantageously employed to eliminate the effects of static induction in the transmission of articulate speech.

In telegraphy the signaling-currents are fat 20 or quantity currents, and though a large portion may be diverted by leak-branches it is a fact, and perhaps obvious, that enough will remain on line to effect the transmission of a perfect signal; but a knowledge of the fact that 25 a telegraphic signal will be well transmitted, notwithstanding a leakage, affords no information that the attenuated and high tension-current impulses, variable as they are in strength, can be passed by leak-branches without rendering the reception of transmitted speech imperfect. If the telephonic impulses were all of one strength, like telegraphic impulses, and if it were possible to assume that 30 a telephone-line, like a telegraph-line, might be provided with leak-branches with equal success, it is not obvious that telephonic impulses, being both undulatory and variable in character—that is, in strength and time—could be transmitted. I have found, however, that weak 35 and strong impulses can be passed by leak-branches equally well, and that variable impulses can be passed by leak-branches without destroying the characteristics of electrical impulses upon which transmitted sound depends.

I am aware that Mowbray's United States 45 Patent No. 243,290 describes earth-branches as being applied to the return portion of a telephonic circuit. My invention, however, contemplates the use of earth-branches for the 50 direct portion of the circuit, whereby static effects thereon may be dissipated. Leak-branches as applied by Mowbray would not serve such

a purpose. Had Mowbray attached leak-branches both to the direct and return portions of the circuit, his invention would have 55 resembled mine.

What I claim, and desire to secure by Letters Patent, is—

1. The combination of a telephonic transmitter, a telephonic receiver, a main line forming that part of a telephonic circuit over which telephonic communication is effected, as distinguished from the return portion of the circuit, and a series of earth-branches distributed along the length of the direct portion of the 65 circuit, substantially as specified.

2. The method of preventing inductive effects upon telephonic lines from interfering with the transmission of articulate speech or sound, which consists in establishing an approximately uniform leakage along the line, which shall not be sufficiently great that it will materially weaken, divert, or dissipate the main-line signaling-impulses, substantially as 70 specified.

3. The combination of a telephonic main line, a series of main-line supports insulated from the telegraph-poles, and an occasional support, as specified, electrically connecting the line with a telegraph-pole or its cross-arm, 75 so substantially as described.

4. The combination of a telegraph-pole or pole and cross-arm of wood or other partial insulating material, an iron or other conducting pin set directly in the pole or cross-arm, 85 and a main telephonic line supported by said pin without the intervention of insulating material, as specified.

5. The combination of an iron or other conducting pin to which a main line is immediately attached, set in the pole or the cross-arm of the pole of wood or other partial insulating material, and a lightning-arrester connecting said conducting pin or support to earth. 90

6. The combination of line-wire L, hollow pin F, a pole or pole and cross-arm forming a partial insulator, metal piece V, plug K, and ground-wire W. 95
